UNITED STATES PATENT OFFICE

ARTHUR W. KIMBELL, OF NEWTON CENTER, MASSACHUSETTS

DESIGN FOR A SNAP-FASTENER CAP

Application filed January 9, 1930. Serial No. 34,058. Term of patent 7 years.

To all whom it may concern:

Be it known that I, ARTHUR W. KIMBELL, a citizen of the United States and a resident of Newton Center, in the county of Middlesex and State of Massachusetts, have invented a new, original, and ornamental Design for a Snap-Fastener Cap, of which the following description in connection with the accompanying drawings is a specification.

Referring to the drawings which form a part of my application:—

Fig. 2 is a side elevation of the cap shown by Fig. 1.

I claim:

The ornamental design for a snap fastener cap, as shown.

In testimony whereof, I have signed my name to this specification.

ARTHUR W. KIMBELL.
